UNITED STATES PATENT OFFICE.

HARRY THAYER KINGSBURY, OF KEENE, NEW HAMPSHIRE.

DESIGN FOR A TOY RAKE-HEAD.

SPECIFICATION forming part of Design No. 35,445, dated December 17, 1901.

Application filed November 8, 1901. Serial No. 81,633. Term of patent 14 years.

To all whom it may concern:

Be it known that I, HARRY THAYER KINGSBURY, a citizen of the United States, residing at Keene, in the county of Cheshire, State of New Hampshire, have invented a certain new and original Design for Toy Rake-Heads, of which the following is a description, reference being had to the accompanying drawings and to the letters of reference marked thereon.

10 My invention relates to a design for toy rake-heads; and it consists in a toy rake-head of the shape and configuration herein described and illustrated in the accompanying drawings, in which—

15 Figure 1 represents a front view, and Fig. 2 a rear view, of a rake-head embodying the design.

In the drawings, A represents the rake-head as a whole, which has the projecting 20 teeth a, formed with convex rear faces and

concave front faces, the rake-head being provided at its upper edge with a horizontally-projecting portion b and the side edges of the upper portion of the rake-head tapering downwardly slightly and having shoulders c. 25

The leading feature of the design consists in the rake-head of the shape and configuration described.

Having thus described my invention, what I claim as new, and desire to secure by Letters 30 Patent, is—

The design for a toy rake-head, substantially as shown and described.

In testimony whereof I affix my signature in presence of two witnesses.

HARRY THAYER KINGSBURY.

Witnesses:

F. E. KINGSBURY,

L. G. LITCHFIELD.
